UNITED STATES PATENT OFFICE

168,317

LAVATORY AND CABINET UNIT

Guy G. Rothenstein, Jamaica, N. Y.

Application May 4, 1950, Serial No. 9,705

Term of patent 14 years

(Cl. D4—2)

To all whom it may concern:

Be it known, that I, Guy G. Rothenstein, a citizen of the United States, residing at Jamaica, State of New York, have invented a new, original, and ornamental Design for a Lavatory and Cabinet Unit, of which the following is a specification, reference being had to the accompanying drawing forming a part thereof.

Figure 1 of the drawing is a perspective front view of the design; and

Figure 2 is a top plan view of the unit shown in Figure 1.

The back surface of the rear wall is plain.

I claim:

The ornamental design for a lavatory and cabinet unit, as shown and described.

GUY G. ROTHENSTEIN.
